UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

RADIO RECEIVING SYSTEM.

Application filed June 7, 1921. Serial No. 475,761.

To all whom it may concern:

Be it known that I, ERNST F. W. ALEXANDERSON, a citizen of the United States, residing at Schenectady, in the county of 5 Schenectady, State of New York, have invented certain new and useful Improvements in Radio Receiving Systems, of which the following is a specification.

My present invention relates to radio receiving systems, and more particularly to a 10 system which permits of the simultaneous reception of a plurality of signals upon a single receiving antenna.

It has been discovered that if a long horizontal receiving antenna extending in the 15 general direction of the transmission of signaling waves to be received is grounded at both ends, signaling currents produced in the antenna by waves coming from any particular transmitting station will be strongest 20 at the end of the antenna farthest from the transmitting station while currents produced by waves coming from the opposite direction will be a minimum at that point. 25 Such an antenna is preferably constructed with distributed constants of such value that the current wave therein travels at the same velocity as the other wave. It is also preferably aperiodic so that the strength of the 30 signaling currents produced therein is substantially independent of the wave length.

One of the objects of my present invention is to provide a method of and means for utilizing an antenna of the form described 35 for the simultaneous reception of a plurality of signals of different wave lengths.

While a long horizontal antenna such as that described has decided unidirectional properties, mathematical analysis indicates 40 and experience shows that at the end furthest from the transmitting station small currents will under some conditions be produced by waves coming from the opposite direction even though the end of the antenna 45 nearest the transmitting station is grounded through a resistance approximately equal to the surge impedance of the antenna so that no reflection can occur.

A more specific object of my invention is 50 to provide means for eliminating the effect upon the receiving apparatus of small undesired currents such as those produced in the antenna by reason of the fact mentioned above, as well as by other conditions. Under 55 these circumstances the surge impedance

of the antenna may not be the best impedance to employ in the ground connection of the antenna nearest the transmitting station; therefore in order to attain this object of my invention I provide an impedance 60 which is preferably adjustable in order that the best operating conditions may readily be obtained. One form of impedance which has been found in practice to be convenient 65 consists of a resistance and a series tuned circuit of low impedance. The object of this series tuned circuit is to reflect back over the antenna a wave component of the proper magnitude and phase to neutralize 70 the small undesired waves mentioned. By slightly off tuning this circuit a small amount of capacitive reactance or inductive reactance as may be desired may be introduced to give the desired reflection; in other words, by suitable adjustment of the terminal impedance of the antenna it is possible 75 to prevent any undesired reflection and at the same time produce a reflection of the proper nature to eliminate disturbing effects. An adjustment of this nature, however, will be most effective for one particular wave length to be received. When, therefore, as in the present case, it is desired 80 to receive several wave lengths upon the same antenna, it is necessary to provide 85 separate means for adjusting the reflection to secure the best results for each wave length to be received. This effect may be obtained by using a separate series tuned 90 circuit in series with the resistance for each of the wave lengths to be received. Where 95 the wave lengths are quite widely separated the series tuned circuit which gives the right value of reflection for one wave length will be of such high impedance for currents of other wave lengths that it will have substantially no effect in so far as the other wave lengths are concerned.

The novel features which I believe to be characteristic of my invention are set forth 100 with particularity in the appended claims, my invention itself, however, both as to its organization and method of operation will best be understood by reference to the following description taken in connection with 105 the accompanying drawing in which I have indicated diagrammatically a simple circuit arrangement whereby my invention may be carried into effect.

As indicated in the drawing, I provide a 110

long horizontal antenna which is preferably made up of at least two parallel wires 1 and 2, the opposite ends of which are grounded at 3 and 4. This antenna is preferably so 5 constructed, or its constants so adjusted that current waves flowing therein will travel along its length at the same velocity as that of the signaling waves in space so that the current waves will gradually grow in amplitude 10 as they travel along the conductor. If it is desired to receive signals which approach the antenna from the end 3 the amplitude of the currents set up in the antenna at 3 by the desired signaling waves 15 will be extremely small while at the end 4 the amplitude of these currents will be a maximum. It may, however, be more convenient to locate the receiving station at the end 3. In order to permit of such a location 20 of the receiving station the antenna conductors may be employed as a transmission line for transmitting the desired signaling currents from end 4 to end 3. One way in which this result may be accomplished 25 is to provide at the end 4 a transformer system made up of a primary winding 5 and a secondary winding 6. The primary 5 of this transformer is connected in series with the ground connection and the two 30 terminals of the secondary 6 connected respectively to the conductors 1 and 2, the middle point 7 of this secondary being connected to ground through the primary 5.

By means of the connection described, signaling currents flowing in the same direction in conductors 1 and 2 toward the end 4 of the antenna flow in parallel to ground through the primary winding 5, and are transferred back upon conductors 1 and 2 40 so as to flow in opposite directions through these two conductors. The conductors 1 and 2 thus form the two sides of a transmission line which is closed at the receiving station through primary winding 8 of a transformer. This primary winding 8 has associated therewith as many secondary windings 9, 10, 11 as there are separate signals which are to be received upon the antenna. Each of these secondary windings is associated 45 with a resonant circuit 12, 13, 14, by means of which the different signaling currents to be received are selected and impressed upon the separate receiving sets 15, 16, 17. The signaling currents transmitted 50 from the end 4 of the antenna flow through the two halves of the primary 8 in series. Currents received upon the antenna, however, from waves traveling from end 4 toward end 3, flow through the two halves 55 of the primary 8 in parallel to ground, and hence produce equal and opposite effects in the windings 9, 10, and 11. As a result 60 the receiving apparatus will be unaffected by such currents.

65 In order to prevent the reflection over

the antenna conductors of currents flowing to ground at 3, a variable resistance 18 is provided in the ground connection which should be made approximately equal to the surge impedance of the antenna. I also 70 provide in series with this resistance as many series tuned circuits 19, 20 and 21 as there are separate receiving sets. Each of these series tuned circuits is made up of an inductance 22 and capacity 23, one or both 75 of which should be adjustable, and an adjustable resistance 24.

In adjusting the system, circuit 19, for example, may be adjusted to secure the desired neutralization in the receiving apparatus 80 15. Unless the signals received in the different receiving sets are of closely adjacent wave lengths this adjustment will not give the best results for the operation of receiving sets 16, 17. Circuit 20, therefore, 85 may be adjusted to secure the desired results in receiver 16 and the circuit 21 may be adjusted to secure the desired results in receiving set 17. If the signals are of considerably different wave length, these separate 90 adjustments will produce substantially no effect upon each other, the resistance and reactance of the entire circuit between joint 25 and ground for each wave length depending almost entirely upon the resistance 95 and reactance of the circuit which is approximately in tune for that wave length.

While I have shown and described the preferred embodiment of my invention it will be apparent that my invention is by 100 no means limited to the particular arrangement shown, but that many variations therein may be made without departing from the scope of my invention as set forth in the appended claims.

What I claim as new and desire to secure by Letters Patent of the United States, is:—

1. A receiving system for radio signals comprising a substantially horizontal receiving antenna which has a ground connection at one end including a resistance substantially equal to the surge impedance of said antenna, a plurality of receiving sets associated with said antenna and a plurality 110 of series tuned circuits in said ground connection.

2. A receiving system for radio signals comprising a substantially horizontal receiving antenna which has a ground connection at one end including a resistance substantially equal to the surge impedance of said antenna, a plurality of receiving sets associated with said antenna and a plurality 115 of series tuned circuits of different resonant frequencies in said ground connection.

3. A receiving system for radio signals comprising a substantially horizontal receiving antenna which is grounded at both ends, means at one end of said antenna for 120 125

5 preventing any undesired reflection of electric waves traveling along said antenna in a direction different from that of the waves to be received, a plurality of receiving sets associated with said antenna, and means for producing a reflection of waves in said antenna to eliminate the effect in each of said receiving sets of waves traveling along said antenna in a direction different from that 10 of the wave to be received.

15 4. A receiving system for radio signals comprising a long horizontal receiving antenna, means for conveying signaling currents from a point in said antenna where the signals to be received are strongest to a distant receiving station, a plurality of receiving sets at the receiving station, means at another point in said antenna for preventing any undesired reflection of electric waves 20 traveling along said antenna in a direction different from that of the waves to be received, and means for producing a reflection of waves in said antenna to eliminate the effect in each of said receiving sets of waves traveling along said antenna in a direction different from that of the waves to be received.

25 5. A receiving system for radio signals comprising a long horizontal receiving antenna, means for conveying signaling currents from a selected point in said antenna where desired signals are strongest to a distant receiving station, a plurality of receiving sets at the receiving station, a ground

35 connection at another point in said antenna including a resistance substantially equal to the surge impedance of the antenna, and a plurality of series tuned circuits in said ground connection.

40 6. The method of operating a radio receiving system comprising a long horizontal antenna and a plurality of receiving sets associated therewith which consists in transmitting to said receiving sets, currents of different frequencies received from desired 45 stations at a selected point in said antenna where such currents have a desired relation to other currents in the antenna, and eliminating the effect in each of the receiving sets of any undesired currents normally 50 flowing at the selected point by producing a reflection over the antenna from another point of currents of the same frequencies and of equal magnitude, and opposite phase to the undesired currents.

55 7. The method of eliminating the effect in a long horizontal receiving antenna of undesired currents at a selected point where signaling currents from a plurality of desired stations have a desired relation to 60 other currents in the antenna which consists in reflecting over the antenna from another point a plurality of currents of equal magnitude and opposite phase to the undesired currents.

In witness whereof, I have hereunto set my hand this 6th day of June, 1921.

ERNST F. W. ALEXANDERSON.
